MEDICAMENT FOR THE TREATMENT
OF BURNSRussel J. Fosbinder, Short Hills, N. J., assignor
to The Maltbie Chemical Company, Newark,
N. J., a corporation of New JerseyNo Drawing. Application January 7, 1935,
Serial No. 705

4 Claims. (Cl. 167—63)

This invention relates to medicaments or dressings for the treatment of burns by the application of tannic acid, the value of which for the purpose is now widely recognized. One object of the invention is to provide a tannic acid medicament, preferably in the form of a non-drying ointment which can be easily applied to the injured surface with the assurance that the tannic acid will be quickly effective. Another object is to provide a tannic acid ointment which will permit bandages to be removed from the burned area without pain or injury to the underlying tissues. A further object is to provide a tannic acid ointment which can itself be removed from the burned surface by the use of water alone. To these and other ends the invention comprises the novel composition of matter hereinafter described.

An important feature of the invention is the use of a base or menstruum which is readily emulsifiable, in water, preferably spontaneously, so that an ointment which contains a wax will not be repelled by a watery exudate of the burned surface but will diffuse in the same and thereby bring the tannic acid quickly into contact with the injured tissue. The most effective emulsifying agent for the purpose is sulphonated oil, and I have found that for the best results the interfacial surface tension of the oil-wax and water interface should be well below 0.5 dyne per centimeter at about 65° C. I have also found that the desired low interfacial surface tension is best obtained by the use of a mixture of sulphonated oils, of different surface activities, in such proportions that the "net" tension, so to speak, is such as will give the desired capability of easy, preferably spontaneous, emulsification. Particularly good results have been obtained in that direction by the use of a sulphonated oil containing a substantial amount of higher fatty ("wax") alcohol or alcohols, with only a small amount of glycerol or glyceride, for instance sulphonated sperm oil, of which the oil on the market with the trade name Nopco No. 1216 is a good example. The sulphonated sperm oil should be neutral. The other oil may be a sulphonated petroleum oil, preferably about the same as ordinary glycerin in viscosity, or a sulphonated vegetable oil, for example sulphonated castor oil (commonly known as Turkey-red oil) which contains a relatively large amount of glyceride and little if any of the higher alcohols. When Turkey-red oil is employed it may be acid in reaction. For the second oil good results have been obtained with the grade known as Nopco

No. 1765, and also with that known as Nopco CT 2F.

The relative amounts of the two oils needed to give a desired easy emulsification can be readily found by trial, but it can be said that in general, using Nopco oil No. 1216 (sperm) and Nopco oil CT 2F (petroleum oil) or acid Turkey-red oil, a ratio, by weight, of about 3:2 has been found satisfactory.

An important advantage of the use of the mixture of sulphonated oils is that the resulting menstruum can carry a large enough amount of bland ingredients, solid and liquid, to produce an ointment of smooth texture, of sufficient softness for easy application, and yet of sufficient viscosity to remain in place well at the body temperature of the burned surface,—and still leave the ointment readily emulsifiable; and this without using a large amount of the emulsifiable menstruum. Thus the bland ingredients,—consisting of, say, neutral white paraffin oil of medium viscosity, white wax, and solid paraffin,—may constitute more than fifty per cent of the whole ointment, by weight, and the sulphonated oil menstruum no more than fifteen per cent, and still give a medicament having the desirable therapeutic and physical properties referred to. Using the three bland ingredients named, with the sulphonated oil ranging from about 12 to 25 per cent and a wax (beeswax and solid paraffin) content of about 23 per cent, the paraffin oil may vary from about 30 to 40 per cent, depending on the viscosity desired. If white wax is used without solid paraffin a little borax, say .75 to 1 per cent, may be added to assist in emulsification, but borax tends to make the ointment gritty when solid paraffin is present.

Another advantage of the emulsifiable menstruum or base is that if the ointment carries an antiseptic the latter will also be brought into the most effective contact with the injured tissues, along with the tannic acid. So, also, a local anesthetic or analgesic. As an antiseptic a creosote or phenolic derivative may be used to advantage, preferably amyl meta cresol, and as an analgesic I prefer p-ethyl aminobenzoate, also known as benzocaine, but any other compatible substance of like properties may be used for the purpose.

A further advantage of the quick emulsifying property of the ointment is that it makes a relatively small tannic acid content as effective as a much larger amount in an unctuous dressing of the usual character. If the ointment emulsifies

- readily in the aqueous exudate of the burned surface the tannic acid is brought quickly into contact with the injured tissues and tanning occurs rapidly. On the other hand, if the emulsification is slow, only the tannic acid in the contiguous layer of the ointment reaches the burned surface quickly, so that unless this layer carries a relatively large amount of tannic acid the desired tanning is delayed. With a sulphonated oil content of about 15 per cent and bland ingredients about 55 per cent, a tannic acid content of 5 to 10 per cent has been found satisfactory, 7 per cent being the preferred amount. It has also been found that tannic acid of the technical grade is more efficacious than the pure acid. The acid is preferably incorporated in the form of an aqueous solution of about 25 per cent concentration. A relatively low water content, say 15 to 30 per cent, is desirable, as the water is then so well surrounded by the unctuous or oily material that the loss of water by evaporation after the dressing is applied to the burn is minimized and the ointment does not become dry or stiff.
- 25 The preferred formula for the ointment is the following, which has been found to be thoroughly efficient:

	Per cent
30 Sulphonated oil—	
Neutral sperm oil	8.6
Neutral petroleum oil or acid	14.85
Turkey-red oil	6.25
35 Bland ingredients—	
White paraffin oil, medium	33
Solid paraffin, melting point 55°-60° C.	13.9
White wax (beeswax)	9
Tannic acid, technical	7
40 Water	21.2
Amyl meta cresol	0.04
p-ethyl aminobenzoate (benzo- caine)	1
	1.04
45	99.99

50 In compounding the ointment the sulphonated oil component and the bland ingredients are heated together to about 75° C., with stirring. When the mix is homogenous the amyl meta cresol is stirred in, after which the tannic acid solution, at about 80° C., is added slowly, with constant stirring. When the mass has partly

cooled the benzocaine is added, the stirring being continued until the ointment has cooled to about 30° C., after which it is allowed to set.

5 The ointment may be packaged in collapsible tubes, and can be spread directly on the burned surface, or, more conveniently, on the bandage which is to be applied to the injured area. An ordinary wooden tongue-depressor is useful for spreading the ointment but a metal spreader may be employed if the blackening incident to simultaneous contact with metal and air is not objectionable.

10 It is to be understood that the invention is not limited to the specific details described above but may be embodied in other forms without departure from its spirit as defined by the following claims:

15 I claim:

1. An ointment for the treatment of burns, containing tannic acid in aqueous solution, and 20 a sulphonated oil menstruum comprising neutral sulphonated sperm oil and neutral sulphonated petroleum oil in the ratio, by weight, of about 3:2, and in total amount to render the ointment spontaneously diffusible in water. 25

2. An ointment for the treatment of burns, containing tannic acid in aqueous solution, and a sulphonated oil menstruum comprising neutral sulphonated sperm oil and acid sulphonated castor oil in the ratio, by weight, of about 3:2, 30 and in total amount adapted to render the ointment spontaneously diffusible in water. 35

3. A tannic acid ointment for the treatment of burns, which contains tannic acid in aqueous solution, and which also contains a sulphonated oil menstruum, giving an oil-water interfacial surface tension less than 0.5 dyne per centimeter, in amount rendering the ointment spontaneously diffusible into water, and which ointment contains an ointment base. 40

4. A tannic acid ointment for the treatment of burns, which contains tannic acid in aqueous solution, in a menstruum containing sulphonated oils of different oil-water interfacial surface tensions, proportioned to give together an oil-water 45 interfacial surface tension less than 0.5 dyne per centimeter and in amount rendering the ointment spontaneously diffusible in water, one of said oils containing a higher fatty alcohol and the other substantially free from such alcohols, 50 and which ointment contains an ointment base.

RUSSEL J. FOSBINDER.
